SPACED WAVE KEYING

"R" Lee Hollingsworth, Riverhead, N. Y., assignor
to Radio Corporation of America, a corporation
of Delaware

Application July 8, 1943, Serial No. 493,846

18 Claims. (Cl. 250—8)

The transmission of mark and space wave keying is not new in principle since it was one of the earliest forms of keying in high power radio transmitters. The older method of receiving such mark and space wave keying depended on the selectivity of the receivers to discriminate against the unwanted spacing wave. A newer conception utilizing both the mark and space waves to approximately double the effective signal strength at the receiver is herein described.

It is one of the objects of the present invention to provide an improved system for receiving mark and space wave or frequency shift keying to accomplish the effective signal increase as mentioned above.

It is another object of this invention to provide in combination with such a method of reception the means for alternately supplying the automatic volume control circuit with rectified mark and space wave energy for automatic gain control purposes.

It is still another object of this invention to provide a mark and space wave receiver having two commonly excited intermediate frequency amplifiers, one to receive the mark wave energy, while the other receives the space wave energy and to provide the means for rendering the output of one of the channels non-operative, while the other channel is operative and vice versa, to insure that the intermediate frequency band width looking into the keyer or translator system shall never be wider than the band width possessed by either one of the two intermediate frequency amplifying channels.

The description of my invention follows, and in this description reference is made to the attached drawings in which Fig. 1 shows schematically a diversity receiver for use in radio telegraph and telephone receiving work, and including the novel features of my means of receiving mark and space wave keying. Fig. 2 is a modification of the arrangement of Fig. 1.

In Fig. 2, I show my receiver utilizing the principle of mark and space wave keying together with my improved means for supplying automatic volume control voltage alternately from the mark and space wave energy for simultaneously rendering the space wave output circuit totally inoperative when mark wave signal energy is being received, and vice versa and for operating the signal translating or recording circuits.

Referring specifically to Fig. 1, the parts are identified as follows: Numerals 1, 2 and 3 indicate receiving antennae that are normally separated from one another by several wave lengths. These

antennae are shown connected respectively to radio frequency amplifiers 4, 5, and 6. The output of these radio frequency amplifiers are connected to detectors and intermediate frequency amplifiers 7, 8 and 9. Each of the radio frequency amplifiers have two tuned output circuits shown at 10, 11, 12, 13, 14 and 15. These output circuits are shown inductively coupled to tuned circuits 16 and 17, 18 and 19, and 20 and 21. 10 Each of the tuned output circuits are shown connected to rectifiers 22, 23, 24, 25, 26 and 27. Ground potential throughout Fig. 1 is indicated by numeral 28. 29 represents a direct current meter to indicate the space wave rectified output energy while 30 represents a direct current meter for indicating the mark wave energy output. 31 is a terminating resistance for the space wave current rectifiers 23, 25 and 27. Tube 32 is a one-way electron discharge device with its cathode connected to the upper end of resistance 31 and its anode connected by leads 33 in the automatic volume control circuits for the radio frequency amplifiers in units 4, 5 and 6 and/or the amplifiers in units 7, 8 and 9. 20 25 34 is a keying tube having its cathode also connected to the upper end of resistance 31 and its anode connected by source 35 and resistance 36 to ground. Source 35 furnishes the plate supply for tube 34 while in resistance 36 is developed a suitable negative blocking bias for the grids of the tone modulator tubes 42 and 43. 30 31 is a second electron discharge tube which is, in a sense, a signal keying tube having its control grid also coupled to the upper end of resistance 31 and its anode connected by source 38 and resistance 39 to ground. This tube provides automatic volume control voltage in the absence of both mark and space wave energy. A tone supply is coupled to the primary windings 40 of a 40 transformer, the secondary winding 41 of which is coupled to the control grids of the balanced tone modulator tubes 42 and 43. The primary winding of a pushpull transformer 44 is connected in a conventional manner to line terminals 45 46. The keyed tone is supplied from 45 to recording apparatus as desired.

The resistances 46 and 48 together with condenser 47 comprise a direct current filter, serving as a time constant in the automatic volume control circuit. Similar arrangements have been shown in my U. S. Patent #2,104,324, dated January 4, 1938, and U. S. Patent #2,243,423, dated May 27, 1941.

49 is a resistance in the direct current path 55 including the marking current meter 30 and rec-

tifiers 22, 24 and 26. Note that the upper end of this resistance 49 is connected through resistor 48 of the AVC filter network to the leads 33, and also to the control grid of the keying tube 34.

In operation let us assume that the carrier frequency assignment of the mark wave is 10,000.500 kilocycles. The energy from the antennae is amplified by radio frequency amplifiers 4, 5 and 6 in the usual manner and passed on to receiver units 7, 8, and 9 where the frequency of the incoming wave signals are changed to desired intermediate frequency using the well known superheterodyne principle. Within units 7, 8 and 9, if desired, a second means of conversion to still a lower intermediate frequency might be employed. Within these receiver units two intermediate frequency channels may be provided for separately amplifying the mark and space wave energies which are finally rectified by rectifiers 22, 23, 24, 25, 26 and 27. On the other hand, the mark and space wave energy as illustrated in Fig. 1 is amplified by a common intermediate frequency amplifier having sufficient bandwidth to pass both wave energies and a filter means provided for separating the mark and space wave signals before they are passed to their respective rectifiers.

Let us assume that the final intermediate frequency chosen be 50 kilocycles and that the amplifier or filter system used to pass the mark wave signal be tuned to this value, and that the intermediate frequency amplifier or filter system used to pass the space wave energy be tuned and centered at 50.500 kilocycles per second. If the transmission to be received has a frequency shift-displacement of 500 cycles per second, when the incoming mark wave signal is centered through the intermediate frequency amplifier it would likewise follow that the space wave signal would automatically be centered through the intermediate frequency amplifier 500 cycles removed.

Let us assume that carrier wave signals are being received and that the transmitter radiation is taking place on the space wave frequency, and that rectifiers 23, 25, and 27 are passing rectified currents through space indicating meter 29 and terminating resistance 31. Connected above resistance 31 is the one-way electron discharge tube 32 that passes direct current into the AVC supply 33. Also connected to the negative side of resistance 31 is the cathode of keying tube 34. This makes the grid of this tube more positive relative to the cathode and causes this tube to be more than normally conductive and an increased current as a result thereof is drawn by source 35 through resistance 36 during spaces. The negative potential drop developed across resistance 36 is applied to the control grids of the balanced tone modulator tubes 42 and 43 to increase the normal blocking voltage which is applied to these tubes, thereby preventing noise currents which might occur (during space) from actuating this balanced modulator stage to send out keyed tone and thereby improperly operate the recording mechanism. Thus, in my novel system, the space wave is dually used to supply automatic volume control voltage at resistance 31 and at the same time to render the keying tube 34 and balanced modulator including tubes 42 and 43 inoperative under conditions when reasonable signals are being received.

If, during this period of idle transmission the space wave should be removed completely or fade to a very low input level, bias supply tube 37 becomes conductive to supply the automatic volume control potential. Explaining this action in de-

tail, the control grid of tube 37 is connected to the upper end of resistance 31 so that as the space wave signals fade out, the grid of 37 becomes more positive with respect to the grounded cathode of this tube and current is drawn through resistance 39 and source 38, thus supplying a potential drop in resistance 39 which is impressed by way of resistance 46 on the automatic volume control circuit. Thus the tube 37 supplies through resistance 46 an automatic volume control voltage in the absence of, or reduction of, signal energy beyond a usable value.

Let us now assume that transmission of intelligence begins and that the signal impulses of the mark wave energy now is passed by rectifiers 22, 24 and 26 through marking meter 30 and through the terminating resistance 49 which is the common output load for these rectifiers. At this time there is no space wave energy flowing through resistance 31 and therefore keying tube 34 becomes less conductive. This is because the cathode of tube 34 becomes less negative, while the control grid thereof which is coupled to the upper end of resistance 49 becomes more negative by virtue of the voltage drop produced by the rectified mark wave signal current across terminating resistance 49. The tube 34 as a consequence is instantaneously biased to cutoff or near cutoff as a result of the application of more negative potential to its control grid and less negative potential to its cathode. With the current through tube 34 greatly reduced or entirely cutoff the blocking bias developed across resistance 36 is reduced and this allows the control grids of balanced modulator tubes 42 and 43 to be biased normally, thus allowing the tone supply to be amplified and passed to the line 45.

It should be appreciated that in my improved system when space wave energy is being received, if heavy static crashes are present, the instantaneous feeding to the automatic volume control circuit of the potential developed as a result of the said static across the resistance 31 instantaneously decreases the gain of the receiver and simultaneously increases the conductivity of keyer tube 34. This practically precludes the possibility of static crashes actuating the balanced modulator tubes 42 and 43, as a result of the fast AGC action taking place through diode 32, which instantaneously increases the bias on balanced modulators 42 and 43, and which simultaneously knocks the gain of the receiver downward. It is intended that resistance 31 shall be somewhat larger than resistance 49 to insure that this desired control action originating across resistance 31 will always be started in advance of any unwanted action that may otherwise result from noise currents passing through resistance 49. With the loss of space wave energy and the application of mark wave energy the automatic volume control voltage developed in resistance 49 may not be supplied as rapidly. However, if found desirable, the time constant values of resistances 46 and 48 and condenser 47 may be reduced in size to allow, for all practical purposes, the same rate of automatic volume control compensation as is present during the reception of space wave energy.

In the modification described in detail above and illustrated in Fig. 1, I have shown a plurality of receivers in a diversity system. It will be understood, however, that single receivers may be used. Such modification obviously requires merely that the receivers not used are discon-

5 connected from the automatic volume control circuit and from the mark and space direct current paths through space and mark meters 29 and 30.

10 In the embodiment illustrated in Fig. 2, a single receiver system is shown, comprising an antenna 50 for collecting magnetic wave energy and feeding the same to a radio frequency amplifier 51. The output of 51 is connected to the input of a receiver in 52. Within the unit 52 there is included the usual frequency converting means as used in superheterodyne receivers to change the frequency of the incoming wave energy to the desired intermediate frequency. The unit 52 also includes an intermediate frequency amplifier and it is assumed that two intermediate frequency amplifying channels are present therein as previously explained in connection with Fig. 1. The two channels include filters for separating the currents of reduced frequency, representing mark and space. 53 and 54 represent tuned output circuits coupled to the intermediate frequency amplifying channels and these tuned output circuits are coupled to triode rectifying tubes 55 and 56, respectively, by way of tuned circuits 53' and 54'.

15 In the description which follows, it is assumed that the rectifier tube 55 passes the spacing wave energy from a frequency shift transmitter, and that rectifier 56 passes the marking wave energy from said frequency shift transmitter. Throughout this figure 57 represents ground and it will be noted that the cathode of tubes 55 and 56 are grounded, while the anodes thereof are connected to tuned circuits 53' and 54' and coupled by said tuned circuits 53' and 54' to tuned circuits 53 and 54, respectively. One end of the tuned circuits 53' and 54' are connected 20 as shown to the cathodes of triodes 58 and 59. The anodes of triodes 58 and 59 are connected to ground by resistors 64 and 65, respectively, so that the mark and space wave rectified currents are passed alternately through series triodes 58 and 59 and through terminating resistances 64 and 65 to ground and back to the cathodes of rectifiers 55 and 56, respectively.

25 The cathode of keying tube 60 is connected to the negative potential end of resistance 64 and during the reception of space wave energy the cathode becomes more negative relative to the control grid which is connected to the negative terminal of resistance 65, so that this tube on the reception of space wave energy is rendered more conductive. As a consequence the anode of tube 60 due to the action of battery 61 thus draws more current through resistance 62, thus providing a higher blocking bias at the point 30 63 which is connected to the grid electrodes of the tubes of the balanced modulator circuit which is similar to those shown in Fig. 1. Note that the cross in the lead to the grids of the balanced modulators indicates the point at which the same would be broken in Fig. 1 and Fig. 2 to connect the receiver of Fig. 2 to the balanced modulators of Fig. 1. This high blocking bias at 35 63 biases the modulator tubes beyond cutoff so that no tone can be sent out for recording.

40 When the space wave signal energy ceases to flow through resistance 64, the cathode of keying tube 60 becomes less negative and this tube is presently or instantaneously rendered nearly or completely non-conductive with the application of negative potential to its control grid when the marking wave energy is impressed on 45 54, rectified in tube 56 and flows through tube

59 and resistance 65 to ground. As a consequence of this increase in negative potential at the upper end of resistance 65 and on the control grid of tube 60, the current through tube 60 is reduced or shut off so that the potential drop in 62 is reduced, thereby greatly reducing or reducing entirely the negative blocking voltage present at 63, which in normal operation allows the balanced modulator tubes to become conductive, amplify a tone and supply the same from the output transformer over lines to the recorder or translator system.

50 The cathode end of tube 58 is coupled by a one-way tube 67 to the automatic volume control circuit 68, which includes resistance 66 and an adjustable portion of resistance 62. The cathode end of tube 59 is also coupled in a like manner to the automatic volume control circuit through the uni-directional device 67. The control grid of tube 59 and the control grid of rectifier 56 are coupled to the cathode of tube 58, that is, to a point on the space wave rectifier circuit, while the control grid of tube 58 and the control grid of rectifier 55 are coupled to the cathode of tube 59, that is, to a point on the rectifying circuit for the mark wave energy.

55 When the space wave current is present, rectified current passes through rectifier 55, tube 58, resistance 64, and ground, and automatic volume control potential is supplied through the unilateral device 67 and at the same time is applied to the control grid of rectifier 56 and the control grid of series tube 59 to render the marking channel completely inoperative. This is because the negative potential at the cathode end of triode 58 is applied to the control grids of rectifier tube 56 and tube 59, thereby increasing their impedance. Conversely, when the marking wave signals are received and rectified in 56 and rectified current flows through 56, tube 59, and resistance 65 to ground and back to the cathode of 56, automatic volume control voltages are supplied from the cathode of tube 59 through the unilateral device 67 to the automatic volume control circuit. 60 The negative potential on the cathode of 59 which increases in the presence of mark currents is also supplied to the control grids of tube 58 and 55 to increase the impedance thereof to render the spacing wave rectifier path non-conductive. Thus, the effective band width of the receiver or rectifier system looking into the keyer and associated transmitter equipment will never be wider than that band width passed by one of the intermediate frequency amplifying channels, since 65 during mark the spacing channel is effectively shut off, while during space the marking channel is effectively shut off.

60 In the modification of Fig. 2, resistance 66 is of sufficient value to allow the required amount of automatic control voltage to be built up and applied to the automatic volume controlled tubes by way of connector 68. Here, as in Patent 2,104,324, Fig. 3, resistance 62 supplies AGC voltage in absence of signal energy as well as blocking bias for balanced tone modulators.

65 It will be understood that the control grids of tubes 58 and 59 may be, if desired, connected to the automatic volume control leads 68 instead of to the cathodes of tubes 59 and 58, respectively.

70 A very particular point of interest in this invention is the almost total discrimination of static and atmospheric noises except during the actual transmission of signalling energy and the particular reduction of the effects of atmospheric noises when space wave energy is being received,

since this energy and likewise atmospheric noises that are received during the time when the space wave circuit is conductive renders the keying tube more conductive causing no change in the translator system.

It is especially appreciated that the space wave channel may not be rendered completely inoperative during marking to utilize the inherent noise reduction possibilities. If, during markings, a heavy atmospheric impulse is received, if part of this impulse flows through the spacing channel there will be an equalizing effect across resistance 62 since the space and mark wave channels are actuating tube 60 in opposite phase relationship. Thus by adjustment of the automatic volume control to the space channel noise reduction can be accomplished, and furthermore, this adjustment may be automatic as a function of the relative noise current strengths.

In my system then, I show a new and improved means for and methods of automatic volume control, together with a means and method for rendering automatically the intermediate frequency amplifying channels alternately non-conductive to improve the overall operation of the system from a signal to noise ratio viewpoint by allowing only the band width required to pass the keying components to be connected to the keyer and translating system.

Therefore the scope of this invention is to be limited only by the fact and spirit of this specification, and by the claims appended hereto.

I claim:

1. In apparatus of the class described, a source of potential representing one signalling condition, a source of potential representing a second signalling condition, an electron discharge tube having a control grid, and a cathode and having an anode arranged to be coupled to recording means, a connection from one of said courses to the control grid of said tube and a connection from the other of said sources to the cathode of said tube.

2. In apparatus of the class described, means including two grid controlled rectifiers for deriving from wave energy, keyed by signals from one signalling frequency to a second signalling frequency, a first potential representing one of said signalling frequencies and a second potential representing the other of said signalling frequencies, a keying tube having a control grid, and a cathode and having an anode coupled to an output circuit, connections for applying the potential derived by one of said rectifiers to the control grid of the other rectifier and to the control grid of said keying tube, and connections for applying the potential derived by the other of said rectifiers to the control grid of said one rectifier and to the cathode of said keying tube.

3. In apparatus of the class described, a source of current representing one signalling condition, a path including an impedance in series with said first source, a source of current representing a second signalling condition, a path including an impedance in series with said second source, an electron discharge tube having a control grid, and a cathode and having an anode coupled to an output circuit, connections from one of said impedances to the control grid of said tube and connections from the other of said impedances to the cathode of said tube.

4. In apparatus of the class described, means including two grid controlled rectifiers for deriving from wave energy, keyed by signals from one signalling frequency to a second signalling fre-

quency, a first current representing one signalling frequency, and a second current representing the other signalling frequency, a path including an impedance in series with one of said rectifiers, a

5 path including an impedance in series with the other of said rectifiers, a keying tube having a control grid, and a cathode and having an anode coupled to an output circuit, connections from one of said impedances to the control grid of said keying tube, connections from the other of said impedances to the cathode of said keying tube, a connection from one of said impedances to the control grid of one of said rectifiers and a connection from the other of said impedances to the control grid of the other of said rectifiers.

5. In apparatus of the class described, an amplifier of controllable gain responsive to wave energy keyed from a first frequency representing a first keying condition to a second frequency representing a second keying condition, rectifying means for deriving from said wave energy a first current representing said first signalling condition, and a second current representing said second signalling condition, a circuit including a first impedance wherein said first current flows, a circuit including a second impedance wherein said second current flows, and a gain control circuit coupling said impedances to said amplifier to control the gain thereof.

6. In apparatus of the class described, an amplifier of controllable gain responsive to wave energy keyed from a first frequency representing a first keying condition to a second frequency representing a second keying condition, two rectifiers for deriving from said wave energy a first current representing said first signalling condition, and a second current representing said second signalling condition, a circuit including a first impedance wherein said first current flows, a circuit including a second impedance wherein said second current flows, a gain control circuit coupling said impedances to said amplifier to control the gain thereof, a keying tube having a control electrode, a cathode, and an output electrode connected to a load, a connection between the control grid of said tube and one of said impedances and a connection between the cathode of said tube and the other of said impedances.

7. In apparatus of the class described, an amplifier of controllable gain responsive to wave energy keyed from a first frequency representing a first signalling condition to a second frequency representing a second signalling condition, two grid controlled rectifiers deriving from said wave energy a first current representing said first signalling condition, and a second current representing said second signalling condition, a circuit for one of said rectifiers including a first impedance wherein said first current flows, a circuit for the other of said rectifiers including a second impedance wherein said second current flows, a gain control circuit coupling said impedances to said amplifier to control the gain thereof, a connection between the impedance in the circuit for one of said rectifiers and the control grid of the other rectifier, and a connection between the impedance in the circuit for the other of said rectifiers and the control grid of said one rectifier.

8. In apparatus of the class described, two rectifiers for deriving from wave energy, keyed by signals from one signalling frequency to a second signalling frequency, a first potential representing one of said signalling frequencies and a second potential representing the other of said

signalling frequencies, a keying tube having a control grid, and a cathode and having an anode connected to recording means, connections including a grid controlled tube impedance in series with one of said rectifiers for applying the potential derived by one of said rectifiers to the control grid of said keying tube, connections including a grid controlled tube impedance in series with the other of said rectifiers for applying the potential derived by the other of said rectifiers to the cathode of said keying tube, connections for applying the potential derived by said one of said rectifiers to said second named grid controlled impedance and connections for applying the potential derived by the other of said rectifiers to said first named grid controlled impedance.

9. In apparatus of the class described, two grid controlled rectifiers for deriving from wave energy, keyed by signals from one signalling frequency to a second signalling frequency, a first potential representing one of said signalling frequencies and a second potential representing the other of said signalling frequencies, a keying tube having a control grid, and a cathode and having an anode connected in an output circuit, connections including a grid controlled tube impedance in series with one of said rectifiers for applying the potential derived by one of said rectifiers to the control grid of said keying tube, connections including a grid controlled tube impedance in series with the other of said rectifiers for applying the potential derived by the other of said rectifiers to the cathode of said keying tube, connections for applying the potential derived by said one of said rectifiers to said second named grid controlled impedance, connections for applying the potential derived by the other of said rectifiers to said first named grid controlled impedance, connections for applying the potential derived by said one of said rectifiers to the control grid of said other rectifier, and connections for applying the potential derived by said other of said rectifiers to the control grid of said one of said rectifiers.

10. In signalling apparatus to be used to derive the signals from wave energy comprising a first frequency representing space and a second frequency representing mark, with the energy keyed from mark to space or vice versa, a first rectifier in a direct current path including an impedance, a second rectifier in a direct current path including an impedance, a variable gain amplifier for feeding marking wave energy to one rectifier and spacing wave energy to the other rectifier, connections excited by current in one of said paths for increasing the impedance of the other path, connections excited by current in said other path for increasing the impedance of said one path, and a gain control circuit coupling both paths to said amplifier.

11. In a balanced keying system responsive to two direct currents alternately produced in a spaced wave receiver and representing respectively wave energy keyed from a marking frequency to a spacing frequency, an electron discharge device having electrodes including a cathode, a control electrode and an output electrode, a source of potential and a load impedance, wherein potentials characteristic of said keying are to be produced, connecting said output electrode to ground, a second impedance wherein one of said direct currents flows connecting said control electrode to ground and a third impedance wherein the other of said currents flows connect-

ing said cathode to ground, the arrangement being such that the bias on said control grid relative to said cathode becomes less negative in the presence of one current, more negative in the presence of the other current and remains substantially constant in the event noise voltages cause currents to flow simultaneously in the second and third impedances.

12. In combination a diversity receiving system including a multiple antenna means for collecting wave energy at several locations, a means for amplifying converting and rectifying separately the wave energies collected by said multiple antenna means, a filter system preceding each final rectifier in the receiving system to cause the marking energy of a frequency shift transmitter to be rectified by one rectifier while the spacing energy from said frequency shift transmitter is rectified by another rectifier, a means of combining separately the mark and space energies, a reversing electron discharge tube rendered more conductive by the presence of spacing energy to increase the blocking bias to an associated tone relaying means, said reversing electron discharge tube being biased to or near cutoff by the loss of spacing energy and the application of marking energy, an automatic volume control system that controls instantaneously the gain of the receivers through a one-way electron discharge tube during spacing, said automatic volume control system also controlling the gain of the receivers through a direct current filter during marking, and a second reversing tube to supply a bias to the receivers in the absence of or during a fade of the marking and spacing signal energy.

13. In combination a diversity receiving system including a multiple antenna means for collecting electromagnetic wave energy at several locations, a means for amplifying the incoming electromagnetic wave energy, a means for changing the frequency of the incoming electromagnetic wave energy to a desired intermediate frequency, a two-channel intermediate frequency amplifier contained in each receiver of said diversity receiving system, separate rectifiers for rectifying the electromagnetic wave energy from each intermediate frequency amplifier channel to cause the marking energy of a frequency shift transmitter to be amplified and rectified by one signal channel while the spacing energy from said frequency shift transmitter is amplified and rectified by another signal channel, a means for combining separately the mark and space energies, a reversing electron discharge tube rendered more conductive by the presence of spacing wave energy to increase the blocking bias to an associated tone relaying means, said reversing electron discharge tube biased to or near cutoff by the loss of space wave energy and the application of marking wave energy, an associated automatic volume control system that controls instantaneously the gain of the receivers through a one-way electron discharge tube during spacing, said automatic volume control system also controlling the gain of the receivers through a direct current filter during marking, and a second reversing tube to supply a bias to the receivers in the absence of or during a fade of marking and spacing signal energy.

14. A radio receiving system comprising a first wave amplifying means, a frequency conversion means, a second wave amplifying means commonly excited but possessing two separate wave signal channels, a rectifier to produce direct cur-

rent from each wave signal channel said direct current disposed to pass through a series rectifier and a terminating resistance, an associated reversing tube made more conductive as a result of one signal channel delivering space wave signal energy from a frequency shift transmitter, said reversing tube made less conductive with the loss of space wave signal energy and rendered non-conductive with the application of marking wave signal energy from said frequency shift transmitter to operate an associated tone keyer, said reversing tube also supplying an auxiliary automatic volume control voltage during the absence of or great reduction of marking and spacing wave energy, an automatic volume control system which derives its control voltage alternately from the mark and space signal voltages through two rectifiers utilizing aforesaid auxiliary automatic volume control voltage in the absence of or great reduction of both mark and space signal voltages, a means of rendering the spacing wave channel inoperative when mark wave signal energy is being received and vice versa.

15. In apparatus of class described, a variable gain amplifier for amplifying wave energy keyed in accordance with signals from a first frequency representing space to a second frequency representing mark and vice versa, a rectifier excited by energy representing space signals for producing direct current in the presence of space signals, a second rectifier excited by energy representing mark for producing direct current in the presence of mark signals, an impedance in series with each rectifier, an automatic volume control circuit coupling each of said impedances to said variable gain amplifier for controlling the gain of the amplifier in the presence of mark and space signals, and a gain control tube having input electrodes associated with that impedance in series with the first named rectifier and having an output coupled with said automatic volume control circuit for controlling the gain of said variable gain amplifier in the presence of space signals of reduced or unusable value.

16. In apparatus of class described, a variable gain amplifier for amplifying wave energy keyed in accordance with signals from a first frequency representing space to a second frequency representing mark and vice versa, a rectifier excited by energy representing space for producing direct current in the presence of space signals, a second rectifier excited by energy representing mark for producing direct current in the presence of mark signals, a keying tube coupled with at least one

5 of said rectifiers and controlled by rectified current therein for producing mark and space potentials for recording purposes, an automatic volume control circuit coupling each of said rectifiers to said first named variable gain amplifier for controlling the gain of the amplifier in the presence of mark and space signals, and a second tube having electrodes associated with one of said first named rectifiers and having an output coupled with said automatic volume control circuit for controlling the gain of said variable gain amplifier in the presence of wave energy of reduced unusable value.

10 17. In a signal detecting system, an amplifier of variable gain for amplifying wave energy keyed from a first frequency representing space to a second frequency representing mark and vice versa, a rectifier excited by the wave energy for producing direct current in the presence of space signals, a second rectifier excited by the wave energy for producing direct current in the presence of mark signals, a keying tube coupled with both of said rectifiers and controlled by direct current flowing therein for producing mark and space potentials for recording purposes, an automatic volume control circuit coupling each of said rectifiers to said variable gain amplifier for controlling the gain of the amplifier in the presence of mark and space signals, and a second control tube having electrodes associated with said first named rectifier and having an output coupled with said automatic volume control circuits for controlling the gain of said amplifier in the absence of wave energy of usable strength.

15 18. In apparatus of the class described, an amplifier of controllable gain responsive to wave energy keyed from a first frequency representing a first keying condition to a second frequency representing a second keying condition, two rectifiers for deriving from said wave energy a first current representing said first signalling condition, and a second current representing said second signalling condition, a circuit including a first impedance wherein said first current flows, a circuit including a second impedance wherein said second current flows, a gain control circuit coupling said impedances to said amplifier to control the gain thereof, and a bias supply tube having a control grid coupled to one of said first two impedances and having an output electrode in a circuit including an impedance, and connections including some at least of said last named impedance in said gain control circuit.

"R" LEE HOLLINGSWORTH.
